UNITED STATES PATENT OFFICE

152,178

DESIGN FOR A SPLASH BACK TRIM FOR A STOVE

Bertrand N. Trombley, Birmingham, Mich., as-
signor to The Murray Corporation of America,
Detroit, Mich., a corporation of Delaware

Application March 28, 1946, Serial No. 128,031

Term of patent 7 years

(Cl. D81—25)

To all whom it may concern:

Be it known that I, Bertrand N. Trombley, a citizen of the United States of America, residing in Birmingham, in the county of Oakland, State of Michigan, have invented a new, original, and ornamental Design for Splash Back Trim for a Stove, of which the following is a specification, reference being had to the accompanying drawing, forming a part thereof, wherein:

Figure 1 is a view in front elevation of the splash back trim for a stove, embodying my new design;

Fig. 2 is a top plan view of the trim; and

Fig. 3 is a side view of the splash back trim illustrated in Fig. 1, as viewed from the right-hand end thereof.

I claim:

The ornamental design for a splash back trim for a stove, substantially as shown.

BERTRAND N. TROMBLEY.
